(57) **CLAIM**

The ornamental design for a plant support for a hydroponic system, as shown and described.

DESCRIPTION

FIG. 1 is a perspective view of a plant support for a hydroponic system showing my new design;

FIG. 2 is a top view thereof;

FIG. 3 is an enlarged top view of a portion thereof;

FIG. 4 is a side view thereof; and,

FIG. 5 is a bottom view thereof.

The broken line showing of environmental structures is for illustrative purposes only and forms no part of the claimed design.

1 Claim, 4 Drawing Sheets
